(57) CLAIM

The ornamental design for a gift box, as shown and described.

DESCRIPTION

FIG. 1 is a perspective view of a gift box showing my new design in a closed configuration;

FIG. 2 is a right side view thereof;

FIG. 3 is a left side view thereof;

FIG. 4 is a front view thereof;

FIG. 5 is a back view thereof;

FIG. 6 is a top view thereof; and

FIG. 7 is a bottom view thereof.

FIG. 8 is a perspective view of a gift box showing my new design in a first open configuration;

FIG. 9 is a right side view thereof;

FIG. 10 is a left side view thereof;

FIG. 11 is a front view thereof;

FIG. 12 is a back view thereof; and

FIG. 13 is a top view thereof.

FIG. 14 is a top view of a gift box showing my new design in a second open configuration; and,

FIG. 15 is a bottom view thereof.

The broken lines shown in the drawings are for the purpose of illustrating portions of the gift box that form no part of the claimed design.

1 Claim, 15 Drawing Sheets
